UNITED STATES PATENT OFFICE

170,830

COMBINED VASE AND FRUIT BOWL

Montez Parrish, Blountstown, Fla.

Application June 20, 1952, Serial No. 20,288

Term of patent 7 years

(Cl. D44—19)

To all whom it may concern:

Be it known that I, Montez Parrish, a citizen of the United States of America, residing at Blountstown, in the county of Calhoun and State of Florida, have invented a new, original, and ornamental Design for a Combined Vase and Fruit Bowl, of which the following is a specification, reference being had to the accompanying drawing, forming part thereof.

Fig. 2 is a plan view thereof.

Fig. 3 is a bottom view of a combined vase and fruit bowl with the central cone-shaped member removed.

Fig. 4 is a transverse sectional view.

I claim:

The ornamental design for a combined vase and fruit bowl, as shown.

MONTEZ PARRISH.
